(57) **CLAIM**

The ornamental design for an ergonomic portable paint reservoir and tool holder, as shown and described.

DESCRIPTION

FIG. 1 is a front, side perspective view of an ergonomic portable paint reservoir and tool holder showing our new design with the handle in rearward position and lid stowed on the back;

FIG. 2 is a side perspective view with the lid in place;

FIG. 3 bottom perspective view with the handle in a forward position;

FIG. 4 is an exploded perspective with the lid; and,

FIG. 5 is an exploded top perspective view.

The two sides of the invention are symmetrical mirror images of each other.

The present invention is a container that enables a user to conveniently carry and distribute a quantity of paint or other liquid. The invention additionally provides means of carrying a variety of associated tools.
